UNITED STATES PATENT OFFICE

EMIL J. BERGER, OF HATFIELD, PENNSYLVANIA

DESIGN FOR HOSIERY

Application filed March 3, 1932. Serial No. 43,055. Term of patent 3½ years.

To all whom it may concern:

Be it known that I, EMIL J. BERGER, a citizen of the United States, residing at Hatfield, in the county of Montgomery and State of Pennsylvania, have invented a new, original, and ornamental Design for Hosiery, of which the following is a specification, reference being had to the accompanying drawing, forming part thereof.

In the drawing:

The figure is a view of a stocking showing my new design to substantially actual scale.

I claim:

The ornamental design for hosiery, as shown and described.

EMIL J. BERGER.
